(57) CLAIM

The ornamental design for a beverage container holder for use with cushioned furniture, as shown and described.

DESCRIPTION

FIG. 1 is a perspective view of beverage container holder for use with cushioned furniture showing our new design thereof; FIG. 2 is a slightly reduced top view thereof. Bottom is flat and devoid of surface ornamentation thereof; FIG. 3 is a slightly reduced left elevational view, right side being a mirror image thereof; and, FIG. 4 is a perspective view of the beverage container for cushioned furniture installed on a bed; the broken lines showing a bed and beverage to be supported is for illustrative purposes only and forms no part of the claimed design.
